UNITED STATES PATENT OFFICE.

GEORGE HENRY DUNLOP, OF SOUTH MELBOURNE, VICTORIA, AUSTRALIA.

EXCAVATING APPARATUS.

No. 825,200.

Specification of Letters Patent.

Patented July 3, 1906.

Application filed January 20, 1904. Serial No. 189,842.

To all whom it may concern:

Be it known that I, GEORGE HENRY DUNLOP, civil engineer, a subject of the King of Great Britain and Ireland, residing at No. 17 5 Dundas Place, South Melbourne, in the British State of Victoria, Commonwealth of Australia, have invented a new and useful Excavating Apparatus, of which the following is a specification.

10 This invention relates to improved machinery for excavating, dredging, and transporting earth and other materials with a scoop or scraper (hereinafter called a "scoop") operated from a main power-station and 15 from an outhaul-station by ropes hauled so that the earth and other materials may be filled into it, transported in it, and deposited from it.

20 In this specification the term "forward" indicates that direction in which the scoop is drawn when it is being filled, and the term "backward" indicates the contrary direction. By "setting up" is meant the operation which is the reverse of overturning.

25 The scoop is drawn forward at suitable varying angle of tilt until it is filled, is drawn away backward or forward to the place where its contents are to be deposited, is overturned forward or backward for depositing its contents, and is set up and drawn away to the place where it is to be filled again, all by means of the ropes. Preferably three ropes are employed; but, as hereinafter described, one of these ropes may not 30

35 be required, and the scoop may be operated by two of the ropes under certain conditions. The scoop is a receptacle having a closed bottom, back, and sides and open front and top, though sometimes the top also may be 40 partly or entirely closed. Of the ropes employed to operate the scoop one is connected at the front near the cutting edge. This I name the "main" hauling-rope, and two are connected at the upper part of the scoop.

45 These I name the "forward-hauling" rope and the "backward-hauling" rope. The main hauling-rope and the forward-hauling rope pass forward from the scoop to the drums of winding machinery or to guide-pulleys leading to them placed beyond the extreme forward limit of travel of the scoop. The backward-hauling rope passes backward from the scoop to the drum of winding machinery or to a guide-pulley leading to it placed

beyond the extreme backward limit of travel 55 of the scoop. The ropes may be connected to the scoop by chains or bars or by bridles or bails such as are used with animal-drawn scoops or with the buckets of steam excavating-shovels or the like of usual construction. 60 The three ropes are operated from a main power-station and from an outhaul-station. These stations are combined in one structure or are in two separate structures, according to the nature of the work. Usually the 65 winding machinery for operating the ropes is all placed on the main power-station, and there is a guide-pulley and no winding machinery on the outhaul-station; but there may be winding machinery on each station— 70 as, for example, on the main power-station for the main hauling-rope and for the forward-hauling rope and on the outhaul-station for the backward-hauling rope. In order that the machinery employed in this 75 method may be most effective, the main hauling-rope is connected to the scoop low down, so that the power is applied as directly as practicable to the cutting edge of the scoop, and the forward-hauling rope and the 80 backward-hauling rope are connected to the scoop so high above the bottom that their effect when the scoop is in its normal position for filling or when filled will be mainly or entirely to tilt the scoop and not to draw it 85 along. An arm on the scoop, as hereinafter described, while not essential, is convenient in this respect.

85 The machinery will now be described, and 90 illustrated as far as necessary in the accompanying drawings as used for excavating a channel in earth. (If necessary, the earth may be loosened, as by plowing.) It is assumed that the main power-station is fitted with mechanism by which the winding-drums can be rotated and that the stations can be moved alongside of the channel as the work progresses.

95 In said drawings similar letters are employed to indicate corresponding parts 100 throughout.

105 Figure 1 is a side elevation showing the machinery with the stations combined and the scoop employed in excavating a channel, the earth being deposited on the farther bank. Fig. 1^a shows the scoop in the initial stage of filling; Fig. 1^b, the scoop nearly filled; Fig. 1^c, the filled scoop being drawn

backward to the embankment, and Fig. 1^d the scoop overturned depositing the contents. Fig. 2 is a similar view to Fig. 1, save that the machinery is adapted for depositing the earth on the nearer bank. Fig. 2^a shows the filled scoop being drawn forward, pushing loose earth in front of it. Fig. 2^b shows the filled scoop being drawn forward with the cutting edge clear of the ground, and Fig. 2^c shows the scoop partially overturned backward. Figs. 3 and 4 are similar views to Figs. 1 and 2, respectively, except that the stations are separate; and Fig. 4^a is a plan of the main power-station shown in Fig. 4. Fig. 5 shows the main power-station and the outhaul-station each located outside of the embankments. Fig. 5^a shows the scoop being filled having an arm somewhat D-shaped in outline in side elevation. Fig. 5^b shows the same scoop being drawn forward toward the embankment. Fig. 5^c shows it being overturned forward. Fig. 5^d shows it partially overturned backward, and Fig. 5^e shows it being drawn backward in the overturned position. Fig. 6 shows the main power-station and the outhaul-station combined in a double cantaliver structure located on the ground between the channel and one of the side embankments. Fig. 6^a shows a part cross-section of the structure with the scoop passing under its deck between the fore and hind wheels, and Fig. 6^b is a part plan. In these figures are shown rollers to act as guides at the opening through which the scoop passes under the structure. Fig. 6^c shows a path-plate to facilitate the passage of the scoop when the carrying-wheels of the stations travel on rails. Fig. 7 shows in part section the scoop fitted with runners. Fig. 7^a shows runners of T-section intended to act more especially as guides, and Fig. 7^b shows a scoop with the side plates projecting below the bottom to act as guides. Figs. 8, 8^a, and 8^b show the scoop with lugs or brackets projecting forward from the sides at the front. Figs. 9 and 9^a show the scoop fitted with wheels to facilitate transportation. Fig. 10 shows the scoop having the chains connecting the scoop to the rope used for overturning attached to it down the back when it is to be overturned forward, so that wet or adhesive material may be more effectually ejected, and having guide-links, between the two sides of which the chains connecting the rope used for overturning will travel and be guided. Fig. 11 shows a scoop with closed top and with front only open for transporting soft or fluid material and with a long arm for dredging under water, and Fig. 11^a shows said scoop being used for dredging a channel under water. Fig. 12 shows the main power-station with sloping front up which the scoop may be drawn and upon which it may be overturned. Figs. 13 and 13^a show scoops with central ribs or stiffeners within the bowls of the

scoops and also with bridles having three draft-lines, one to each side and one to the central rib; and on Fig. 13^a is shown an attachment to receive a lever for guiding the scoop when necessary. Fig. 14 shows the scoop overturned backward depositing earth in a layer of desired thickness.

In Fig. 1 is shown in cross-section a channel partly excavated, with an embankment on one side formed of the excavated earth. The scoop S has an arm or raised portion A. The forward-hauling rope R' is connected to the upper part of the arm on the scoop and passes thence to the winding-drum D' on the main power-station M. The backward-hauling rope R² is connected at or near the same part of the arm on the scoop as the forward-hauling rope, passes thence around the guide-pulley P² and to the winding-drum D² on the main power-station. The main hauling-rope R³ is connected to the sides of the scoop, near the mouth, and passes from it to the winding-drum D³ on the main power-station. The outhaul-pulley P² is on the outhaul-station, which station consists in this case of a braced boom and back tie O, projecting from the main power-station M, as shown. The scoop being in the channel where it is to be filled is tilted forward more or less by the rope R', so as to bear mainly or entirely on the cutting edge or on the cutting-plate at the mouth or open front while the main hauling-rope R³ is hauled in, so that the scoop is drawn forward and sinks into the ground, as shown in Fig. 1^a. As it does so the scoop is caused to assume a more backward tilted position under the control of the ropes R' and R² until it reaches the position shown in Fig. 1^b, and so is drawn forward and completely filled. The filled scoop is drawn out backward onto the embankment by the rope R², as indicated in Fig. 1^c, to the place where its contents are to be deposited. It is overturned forward, as shown in Fig. 1^d, by hauling in the forward-hauling rope R', and so the contents are deposited. The scoop is now either drawn into the channel by the rope R' and set up ready to be refilled by the rope R² or it may be set up by the rope R² and be drawn into the channel by the rope R³. If it is required to fill loose earth quite up to the side of the main power-station and at the same time avoid leaving a ridge of loose earth which might be pushed in front of the scoop in filling and be left there when the filled scoop is hauled backward, then there may be fitted alongside of the main power-station a plate or flap down to the ground, which the front of the scoop will be drawn up to, and by means of this plate or flap the earth can be forced back into the scoop.

In Fig. 2 the boom constituting the outhaul-station is shown as constructed so that the scoop can be operated to deposit the excavated earth in embankment on that side of

the channel nearer to the main power-station. The boom passes over the embankment at sufficient height above the ground. When the scoop has been filled, as before described, it is drawn out forward onto the embankment by the rope R^3 , is overturned forward by the rope R' , and is set up and drawn out again by the rope R^2 . When the filled scoop is being drawn forward to the embankment, it may be held, as shown in Fig. 1^b, with the cutting edge down to the ground, so that earth may be pushed in front of the scoop in addition to that contained in it, or the scoop may be drawn out, as shown in Fig. 2^b, with the cutting edge clear of the ground, transporting the earth contained in it only. It is obvious that with a boom of sufficient length for the outhaul-station, as shown in Fig. 2, the excavated earth may be deposited at will on the far side of the channel, as described in connection with Fig. 1, or on the near side, as described in connection with Fig. 2.

In Fig. 3 the outhaul guide-pulley P^2 is borne at a suitable elevation on an independent outhaul-station O beyond the embankment, while the main power-station M is alongside the channel. The operation of the scoop is as described in connection with Fig. 1. In Fig. 4 the main power-station M is placed outside of the embankment, with the winding-drums or guide-pulleys, around which the ropes pass to the drums, placed at suitable elevations, and the independent outhaul-station O , with the guide-pulley P^2 , is placed on the farther bank of the channel, as shown. The operation of the scoop is as described in connection with Fig. 2.

In Fig. 5 the main power-station and the outhaul-station are shown placed one on each side of the channel outside of the embankments. It is obvious that the excavated material may be deposited at will on the far side of the channel or on the near side by operations as described in connection with Figs. 1 and 2, respectively.

The independent outhaul-station, as shown in Figs. 3, 4, and 5, may be adopted where the dimensions of the work are too great to permit the convenient use of a boom for the outhaul-station.

In the constructions shown in Figs. 1, 2, 3, 4, and 5 one or both of the stations must be located beyond the positions where the excavated earth is to be deposited. In some works such location is impracticable or inconvenient. In Fig. 6 the main power-station and the outhaul-station are shown combined in a double cantaliver structure located on one bank between the channel and the side embankment. One cantaliver-arm spans across the channel and constitutes the outhaul-station, as O , with the outhaul guide-pulley P^2 at its outer end. The other arm spans across the embankment and is fitted

with guide-pulleys P' and P^3 at its outer end, around which the forward-hauling rope R' and the main hauling-rope R^3 , respectively, pass to the winding-drums D' and D^3 . This combined structure is so designed that the scoop can be drawn out under it between the wheels underneath the floor or deck on which the winding-drums are placed, as shown in Fig. 6^a. The scoop is filled, as already described, is drawn out onto the embankment by the rope R^3 , is overturned by the rope R' , and is set up and drawn back by the rope R^2 . It is obvious that if the cantaliver-arm carrying the guide-pulley P^2 is sufficiently long, excavated earth can be deposited on the farther bank, so that the earth could be deposited part on one bank and part on the other bank at will. Also the central portion of the framing from which the arms project can be arranged to bestride the channel instead of resting entirely upon one bank. In Figs. 6 and 6^a the main power-station is shown mounted upon road-wheels. It may be desirable to set it upon wheels to travel on rails, &c. In such case a path-plate or floor, as m , may be fitted to the main power-station, so as to bear upon the rails and form a smooth way to facilitate the passage of the scoop over the rails, &c., as indicated in Fig. 6^c. The main power-station (shown in Fig. 6) may have guard-rollers, as m' , to prevent the scoop from striking the wheels when the scoop is from any cause being drawn along not in the usual course fairly opposite to the opening between the wheels. (Shown in Fig. 6^a.) These rollers usually will only be required on the side nearer to the outhaul-station; but they may be fitted on the other side also. Similar guide-rollers, as m^2 , may also be fitted projecting below the under side of the deck upon which the winding-drums are shown in Fig. 6 to prevent the ropes from rubbing against the deck. One such roller, near the side farther from the outhaul-station, will probably be sufficient, and this roller may be double-cone shaped, with the smallest diameter at the middle, so that it may always tend to lead the ropes toward mid width of the opening through which the scoop passes. Obviously with the main power-station shown in Fig. 6 an independent outhaul-station may be employed, if necessary or convenient, instead of the boom, as shown.

It is evident that the direction of travel of the scoop, as shown in any of the figures, forward and backward relative to the main power-station may be reversed by using guide-pulleys at suitable positions.

While essentially the method and machinery is substantially as hereinbefore described, yet to deal with different conditions of work and different classes of materials modifications therein are desirable so that the best results may be obtained.

The machinery may be operated by any

suitable power. A main power-station with mechanism driven by steam will now be described. It is advisable that the operation of the scoop by means of the ropes should be 5 in charge of one attendant, hereinafter called the "driver," placed in such a position, if possible, that he can oversee the scoop throughout its course. (When it cannot be arranged that the driver should oversee the 10 scoop, he may be directed by another attendant, placed in such a position that the latter can oversee it.) A second attendant, hereinafter called the "fireman," will have charge of the steam-generator, the moving 15 of the station, as required by the progress of the work, and other subordinate duties. Where there is an independent outhaul-station, there may be a trolleyman in charge of it, who will move it forward by means of 20 suitable ordinary mechanism. As shown in Figs. 4 and 4^a, the main power-station consists of a strong carriage, mounted on four broad road-wheels and having a platform or deck F near the level of the axles. Upon 25 this platform there is a steam-generator G, a double-cylinder single-drum winding-engine E, suitable ordinary steering mechanism connected to one pair of the wheels, and propelling mechanism connected to the other 30 pair of wheels, so that it can be put into and out of gear with the winding-engine by means of a clutch, as may be necessary from time to time, for moving the station alongside of the channel as the work progresses. Mounted 35 on standards above the platform or deck already described there is an upper platform F' at suitable elevation to enable the driver standing upon it to oversee the scoop throughout its course. Upon this upper platform 40 there is a double cylinder double-drum winding-engine E'. This upper platform will necessarily be higher when the main power-station is placed outside of the side embankment, as shown in Figs. 2, 4, and 5, than will 45 be essential when the station is located on the bank of the channel, as in Figs. 1 and 3. In fact, when the main power-station is located on the bank of the channel, all mechanism and the driver may be upon the one 50 main or lower platform and the upper platform may be dispensed with. In Fig. 4 the main hauling-rope R³ passes from the scoop over a guide-pulley P³, adapted for attachment at varying heights on the standards on 55 the main power-station, and thence to the winding-drum D³ of the main hauling-engine E. The winding-engine E is fitted with the usual brake, clutch, and steam-valve with handle, which may be under the 60 control of the fireman, but which preferably are under the direct control of the driver on the upper platform by means of suitable long handles extending up to convenient positions within his reach. The winding-engine E' has drums D' and D² for winding the

ropes R' and R². These drums are shown in Fig. 4^a placed side by side; but they may be placed tandem, if preferred. There is the usual foot-brake and clutch to each winding-drum and a steam-valve with handle and reversing-gear.

The cycle of operations is as follows for excavating and transporting a scoopful of earth from the channel to the embankment with the machinery described and shown in Figs. 4 and 4^a. When the scoop is drawn out into the channel to the place where it is to be filled, the driver unclutches the drum D², 75 clutches the drum D', tilts the scoop forward onto its cutting-plate by the rope R', applies the brake to the drum D², clutches the drum D³, and admits steam to the winding-engine E. The rope R' is hauled by the winding-drum D', to which power is applied, and the rope R² is restrained by the winding-drum D², so far as may be required, by means 80 of the brake applied to it. The power and the brake are under the control of the driver, who allows the power of the winding-engine or the restraint of the brake to prevail sufficiently, according as he desires the scoop to be held tilted, either more forward or more backward, while it is being drawn forward for filling by the main hauling-rope R³, operated by the independent winding-engine E. 85 When the scoop is filled, it is drawn out and overturned, as already described. When the scoop has been overturned forward and the contents deposited on the embankment, the driver unclutches the drums D³ and D', 90 clutches the drum D², and hauls the scoop outward into the channel. It is evident that if the ropes R' and R² pass off from the drums D' and D² from the same side, either 95 upper or lower, that the direction of the motion by the engine E' need not be reversed, since the direction in which the scoop is drawn by the rope R² is reversed from that in which it is drawn by the rope R', by passing around the guide-pulley P². Otherwise the 100 motion of the engine must be reversed for hauling backward into the channel. When the scoop is being hauled into the channel, it may be necessary to check too fast unwinding of the ropes R' and R³ off the drums D' 105 and D³ by applying the brakes lightly, or friction-clutches, if such are used, to restrain such unwinding. The mechanism and operations for removing a scoopful of earth described in detail in connection with Figs. 4 110 and 4^a is applicable to all the types of machinery shown, subject to such modifications as circumstances may require.

At times it may be desired or necessary to haul the scoop in a direction not at right angles or "square" to the winding-drums. To provide for such case, the winding-engine—as, for example, that shown in Fig. 4^a—may be pivoted, as by a king-bolt K, and have the forward part adapted to slide or roll laterally on 115 120 125 130

a suitable bearing surface B, so that the drums may turn to suit the direction of lead of the ropes.

When the outhaul-station consists of a boom, the scoop may be lifted off the ground when the main power-station is being moved to a new position for excavating or when it is desired to bring the scoop into the line of direction along which it is to be drawn toward the main power-station. In Figs. 1 and 2 the scoop is shown by dotted lines suspended by the rope R².

The booms shown in connection with the power-station may be hinge-jointed to the main structure and have the back ties fitted with such connections, as is usual with cranes and the like, that the outer end of the boom can be raised or lowered, if necessary.

When the filled scoop is drawn forward onto the embankment, it may be overturned backward to deposit its contents and may be drawn back in the overturned position to the place where it is to be again filled by the backward-hauling rope and may be there set up by the forward-hauling rope. The scoop so operated is shown in position being drawn forward onto the embankment, pushing loose earth in front of it in Fig. 2^a, with the cutting edge clear of the ground in Fig. 2^b, and in position partially overturned backward in Fig. 2^c. The arm shown on the scoop is of somewhat triangular outline in side elevation, as already shown in Fig. 1^a, but with the higher part where the forward-hauling rope and the backward-hauling rope are connected over the front of the scoop, as shown. If it is desired to deposit the earth part on the bank farther from the main power-station by overturning the scoop forward and part on the nearer side by overturning the scoop backward, using the same scoop throughout, then the arm may be formed, as shown in Figs. 5^a, 5^b, 5^c, 5^d, 5^e, somewhat D-shaped in outline in side elevation. The point or points of connection of the forward-hauling rope and of the backward-hauling rope are merely altered for alteration of direction of overturning. The scoop is shown in position being filled in Fig. 5^a, in position being drawn out onto the embankment forward in Fig. 5^b, in position being overturned forward in Fig. 5^c, in position partially overturned backward in Fig. 5^d, and in position being hauled into the channel backward in the overturned position in Fig. 5^e. A cross-bar A' is shown in Fig. 13 with rings to which the ropes are connected by chains, &c., which bar may be fixed at either the forward or backward part of the arm, as required, according to the way in which the scoop is to be overturned.

The scoop is shown in Fig. 7 in part section fitted with runners U, upon which it slides along. These runners serve to strengthen the scoop, to reduce wear on the body of the scoop, and to act as guides by gripping or cut-

ting into the ground, so as to prevent or restrain the scoop from deflecting laterally from the proper course along which it is being drawn. These runners may also be formed of T-section, as shown in Fig. 7^a, so that they may tend more effectually to grip or cut into the ground, and so prevent the scoop from deflecting laterally from its proper course; but special ribs may be provided, if necessary, to act as guides. Thus the scoop shown in Fig. 7^b has the sides projecting, as U', below and behind the bottom plate, rounded at the lower back part to form guides to prevent lateral deflection. Similar or equivalent guides may be fitted detachable at will. The runners and guides are not essential to the scoop; but usually the use of runners will be advantageous. The guides will be used only where the nature of the work requires them.

Figs. 8, 8^a, 8^b show a scoop fitted with projecting lugs or brackets J. In Fig. 8 the filled scoop is shown in position with the cutting edge clear of the ground, being hauled forward by the rope R³, connected by means of chains to the sides of the scoop, in Fig. 8^a the scoop is shown overturned forward, depositing the contents, and in Fig. 8^b the scoop is shown tilted forward in position ready to be filled. In Fig. 8 the ropes R' and R² are shown connected to the scoop, as hereinafter described, with links, &c., in such manner that it can be overturned forward suitably for ejecting wet or adhesive materials. In Figs. 8^a and 8^b the rope R³ is connected, by means of a bail or bridle formed of a bar, to the brackets and not directly to the scoop. When the scoop is fitted with brackets, the contents can be deposited without overturning it as far forward as is necessary when the brackets are not used. In Fig. 8 the bracket J is shown detachable. In Figs. 8^a and 8^b the brackets are in one piece with the arm. Plates may be fitted to the brackets where they bear on the ground to form suitable sliding surfaces. These plates may be detachable for renewal.

A scoop fitted with wheels W is shown in Fig. 9. The forward part of the bottom of the scoop is straight and the backward part is curved to a radius somewhat less than the radius of the wheel. This scoop is specially adapted for use when it is desired to deposit the contents by overturning backward; but it may be overturned forward, in which case the arm if used might be of the form shown in Fig. 5^a. When the filled scoop is to be hauled backward to the place where its contents are to be deposited as described in connection with Fig. 1, it may be fitted with wheels W' of smaller diameter, as shown in Fig. 9^a, upon which it travels backward. In scoops having wheels the front or mouth may be splayed out or have splay-pieces fitted to the sides, so as to fill and clear away a suffi-

cient width at each side to allow the wheels to travel freely on the ground excavated and cleared by the scoop.

- In the scoop shown in Fig. 10 the rope R' used for overturning the scoop is connected not at the top of the arm, but lower down at the back of the scoop, so that the scoop may be overturned in such manner that the contents, especially if wet or adhesive, may be more effectually ejected. In such case the rope R^2 may be connected to the scoop by means of the link or links L , extending for a sufficient short distance from the point of attachment to the scoop. The connecting-chains of the rope being used for overturning the scoop will travel and be guided within the links. The scoop shown in Figs. 2^a and 5^a may be similarly fitted at the front when the scoop is to be overturned backward.
- The scoop shown in Fig. 11 has the front only open and when full can be drawn along tilted backward, so that soft or fluid material can be transported without spilling. Thus, for example, dredging of soft mud from under water may be done with a scoop so formed that the contents may not be spilled when the filled scoop is being drawn away and having a handle of sufficient length to act as a guide to the operator when the scoop is under water, as shown in Fig. 11^a.

The independent outhaul-station may be moved along as required by transmitting power from the guide-pulley P^2 by suitable gearing to the wheels or axles. Thus as the guide-pulley P^2 revolves while the scoop is being drawn backward power may be transmitted—as, for example, by chain or spur-wheel and shaft-gearing—for moving the outhaul-station as required for making successive cuts across the channel, or the independent outhaul-station may be fitted with mechanism by which it may be moved by independent motive power.

In Fig. 12 is shown an arrangement of main power-station M according to this invention, which may be adopted for loading wagons, tipping into a hopper or sluice, or onto a traversing band or conveyer or the like, M' . As shown, the main power-station consists of a framework having a suitable sloping front, up which the scoop can be hauled to the place where it is to be overturned and the contents deposited. Any form of outhaul-station hereinbefore described may be used with this type of main power-station, and it may be mounted on wheels and fitted with platform at suitable elevation for the driver, &c., as already described.

The arm or projection on the scoop may be of any suitable construction. Thus it may be formed by carrying the corner angle-irons of the scoop up, bending them around, and attaching them to the sides of the scoop substantially as shown in Fig. 13^a.

The method and machinery herein described for excavating a channel may be employed for various purposes with only such variations as may be necessitated by the nature of the work, the physical characteristics of the materials, and the like.

Although heretofore the main power and outhaul stations are shown located on the ground, they or either of them may be located on floating pontoons, as for dredging, the method of operating the scoop remaining as before.

Where the scoop has a very long cutting edge measured from side to side, it may be found convenient to have a central rib or stiffener C within the bowl of the scoop, as shown in Figs. 13 and 13^a, to support the bottom of the scoop and to prevent bending of the cutting-plate. Further, a third draft-line C' may be attached to this central rib with equalizing-draft bars of suitable ordinary construction where the three ropes meet at the end of the single main hauling-rope proper, as shown in Fig. 13.

In some cases it is required that the earth shall be spread upon the embankment in layers of stated thickness. Where the earth is deposited from the scoop by overturning it forward, then this purpose will be effected by drawing the scoop along controlled by the ropes so that the mouth or cutting edge of the scoop is held at the proper height above the surface upon which the layer is to be spread. When the scoop is overturned backward, the back of the scoop may be closed to s^2 , so that the unclosed depth measured to the top of the arm is sufficient to leave the earth in a layer of the stated thickness, as shown in Fig. 14.

Sometimes it may be necessary in order to bring the scoop laterally to a desired position that it should be guided by hand. For this purpose a staple s or other suitable attachment may be fitted to the side of the scoop, in which a lever s' may be inserted to assist in such guidance, as shown in Fig. 13^a.

The operation of the scoop by means of the main hauling-rope and the backward-hauling rope, dispensing with the forward-hauling rope, will now be described. This operation by the two ropes can be practiced only when the scoop is to be drawn forward from the place where it is filled to the place where the contents are to be deposited and will be expedient only when the direction of draft by the main hauling-rope is parallel or is not far from parallel to the surface upon which the scoop travels or direction of motion of the cutting edge of the scoop when filling. Thus the scoop, as shown in Figs. 2^a, 5^a, 9, or 13, may be operated by the two ropes—the backward-hauling rope R^2 and the main hauling-rope R^3 for filling the scoop, hauling it forward onto the embankment, overturning it backward to deposit the contents,

and hauling it backward into the channel to be again filled, with main power-stations and outhaul-stations, as shown in Figs. 2, 4, 5, and 6. The cycle of operations for excavating and transporting a scoopful of earth is as follows: The scoop being in the place where it is to be filled is drawn forward by the main hauling-rope R^3 until it is filled, is hauled out forward by it onto the embankment, is overturned backward by the backward-hauling rope R^2 for depositing the contents, and is drawn backward by it in the overturned position into the channel to be again filled. When operating with the two ropes only, the main hauling-rope may be connected somewhat higher up and farther back from the front on the sides of the scoop than when the forward-hauling rope R' is used also, so that when the scoop is being drawn along by the rope R^3 its effect may be somewhat to tilt the scoop forward onto the cutting edge and so cause it to cut into the ground—in fact, to give it some of the purpose of the forward-hauling rope R' , previously described. When the scoop has been filled and is being drawn forward onto the embankment, the scoop may be tilted slightly backward, so as to prevent the cutting edge from cutting into the ground or catching against obstructions by applying a slight pull on the top of the scoop by the backward-hauling rope. In order that the line of draft of the main hauling-rope may be as nearly parallel to the surface of the ground upon which the scoop is to be filled, the filling may be done in successive cuts, sloping upward or approximately radiating toward the winding-drum D^2 .

The cutting-plate of the scoop may project outward and downward from the bottom of the scoop, being so formed that it will cut readily into the ground.

When working with two ropes, a steam winding-engine with double cylinders and double loose drums fitted with brakes and clutches to each drum may be used. The scoop will be filled by the rope R^3 , be hauled out by the rope R^3 while tilted backward as may be necessary by the rope R^2 , restrained by applying the brake sufficiently to the drum D^2 , be overturned backward by the rope R^2 , be drawn back again by the rope R^2 , and be set up for refilling by the rope R^3 .

Having now described my invention, what I claim as new, and desire to secure by Letters Patent, is—

1. In combination in apparatus for excavating, dredging and transporting earth and other materials, a main power-station and an outhaul-station in one structure, a scraper and power mechanism and three ropes for operating said scraper whereby earth may be filled into the scraper by hauling it forward, transported in it by hauling it backward and deposited from it by overturning it forward, substantially as described.

2. In combination in apparatus for excavating, dredging and transporting earth and other materials, a main power-station and an outhaul-station in one structure, a scraper and power mechanism and three ropes for operating said scraper whereby earth may be filled into the scraper by hauling it forward, transported in it by hauling it forward and deposited from it by overturning it backward, substantially as described. 75

3. In combination in apparatus for excavating, dredging and transporting earth and other materials, a main power-station and an outhaul-station in one structure, a scraper and power mechanism and three ropes for operating said scraper whereby earth may be filled into the scraper by hauling it forward, transported in it by hauling it either backward or forward and deposited from it by overturning it forward or backward as the work may require, substantially as described. 80

4. In combination in apparatus for excavating, dredging and transporting earth and other materials, a main power-station and an outhaul-station in separate structures, a scraper and power mechanism and three ropes for operating said scraper whereby earth may be filled into the scraper by hauling it forward transported in it by hauling it backward and deposited from it by overturning it forward, substantially as described. 95

5. In combination in apparatus for excavating, dredging and transporting earth and other materials, a main power-station and an outhaul-station in separate structures, a scraper and three ropes for operating said scraper whereby earth may be filled into the scraper by hauling it forward, transported in it by hauling it forward and deposited from it by overturning it forward, substantially as described. 100

6. In combination in apparatus for excavating, dredging and transporting earth and other materials, a main power-station and an outhaul-station in separate structures, a scraper and power mechanism and three ropes for operating said scraper whereby earth may be filled into the scraper by hauling it forward, transported in it by hauling it either backward or forward and deposited from it by overturning it backward, substantially as described. 115

7. In combination in apparatus for excavating, dredging and transporting earth and other materials, a main power-station and an outhaul-station in separate structures, a scraper and power mechanism and three ropes for operating said scraper whereby earth may be filled into the scraper by hauling it forward, transported in it by hauling it either backward or forward and deposited from it by overturning forward or backward as the work may require, substantially as described. 125

8. In combination in apparatus for excavating, dredging and transporting earth and 130

other materials, a main power-station and an outhaul-station in one double cantaliver structure, a scraper and power mechanism and three ropes for operating said scraper whereby earth may be filled into said scraper by hauling it forward, transported in it by hauling it forward toward the extreme outward limit of the main power-station and deposited from it by overturning it forward, substantially as described.

9. In combination in apparatus for excavating, dredging and transporting earth and other materials, a main power-station and an outhaul-station in one double cantaliver structure, a scraper and power mechanism and three ropes for operating said scraper whereby earth may be filled into said scraper by hauling it forward, transported in it by hauling it forward toward the extreme outer limit of the main power-station and deposited from it by overturning it backward, substantially as described.

10. In combination in apparatus for excavating, dredging and transporting earth and other materials, a main power-station and an outhaul-station in one double cantaliver structure, a scraper and power mechanism and three ropes for operating said scraper whereby earth may be filled into said scraper by hauling it forward, transported in it by hauling it backward toward the outhaul-station and deposited from it by overturning it forward, substantially as described.

11. In combination in apparatus for excavating, dredging and transporting earth and other materials, a main power-station and an outhaul-station in one double cantaliver structure, a scraper and power mechanism and three ropes for operating said scraper whereby earth may be filled into the scraper by hauling it forward, transported in it by hauling it backward or forward and deposited from it by overturning it forward or backward as the work may require, substantially as described.

12. In combination with a main power-station and an outhaul-station having suitable power mechanism, a scraper and three ropes for operating said scraper substantially in the manner herein described whereby earth and other materials may be filled into the scraper, transported in it and deposited from it.

13. In combination with a main power-station and an outhaul-station having suitable power mechanism, a scraper having an arm or projection thereon and three ropes for operating said scraper substantially in the manner herein described whereby earth and other material may be filled into the scraper, transported in it and deposited from it.

14. For excavating, dredging and transporting earth and other materials in combination, a main power-station and an outhaul-station with power mechanism, a scraper

and ropes for operating said scraper whereby earth and other materials may be filled into the scraper by hauling it forward, transported in it by hauling it forward and deposited from it by overturning it backward, substantially as described.

15. For excavating, dredging and transporting earth and other materials in combination, a main power-station and an outhaul-station with suitable power mechanism, a scraper and three ropes for operating said scraper whereby earth and other materials may be filled into the scraper by hauling it forward with one part of the scraper bearing upon the ground, transported in it by hauling it away with another part of the scraper bearing upon the ground and deposited from it by overturning it, substantially as described.

16. For excavating, dredging and transporting earth and other materials in combination, a main power-station and an outhaul-station with suitable power mechanism, a scraper and ropes for operating said scraper whereby earth and other materials may be filled into it by hauling it forward bearing upon one part of the scraper, transported in it by hauling it away bearing upon another part, deposited from it by overturning it onto the third part of its surface upon which it is borne when being hauled back to be refilled, substantially as described.

17. In combination, machinery comprising a scraper, a main power-station and an outhaul-station power mechanism, three winding-drums, brakes and clutches to said winding-drums, power-controlling mechanism, manipulating-levers therefor, an elevated platform for the operating attendant and three ropes passing from said winding-drums to points of attachment at the scraper, of which ropes the main hauling-rope is attached near the front of the scraper and the forward-hauling rope and the backward-hauling rope are attached at the upper part of the scraper whereby earth and other materials may be filled into the scraper, transported in it and deposited from it.

18. In combination, a main power-station and an outhaul-station, a main hauling-engine having a winding-drum, a controlling-engine with two winding-drums, a scraper, a main hauling-rope passing from the drum of the main hauling-engine to the front of the scraper, a forward-hauling rope passing from a drum of the controlling-engine to the upper part of the scraper, a backward-hauling rope passing from a drum fitted with a friction-brake on the controlling and from the outhaul-station to the upper part of the scraper whereby said scraper may be drawn along by the main hauling-rope, tilted forward by the forward-hauling rope, tilted backward by the backward-hauling rope and held tilted as

desired by the forward-hauling rope hauled by the controlling-engine acting against the backward-hauling rope restrained by the friction-brake so that earth and other materials may be filled into the scraper, transported in it and deposited from it, substantially as described.

19. For excavating, dredging and transporting earth and other materials by means of a scraper operated by ropes as herein described, an arm or projection on the said scraper with which the ropes engage whereby the control of the scraper by the forward-hauling rope and the backward-hauling rope is facilitated, substantially as described.

20. A scraper having an arm or projection of sufficient length to rise above the surface of the water when being used for excavating and the like under water, hauling means engaging with said arm substantially as described.

21. For excavating, dredging and transporting earth and other materials, a power-station and an outhaul-station with suitable power mechanism combined in one structure, consisting of a framing forming the main power-station and boom projecting therefrom forming the outhaul-station, and a scraper supported and operated by ropes controlled therefrom substantially as and for the purpose described and shown.

22. For excavating, dredging and transporting earth and other materials in combination, a main power-station and an outhaul-station with suitable power mechanism, a scraper having a strengthening-rib within the bowl and ropes for operating said scraper, substantially as described and shown.

23. For excavating, dredging and transporting earth and other materials in combination with a scraper and ropes attached to said scraper, a machine comprising a main power-station and an outhaul-station combined in one double cantaliver structure with suitable power mechanism whereby earth may be filled into the said scraper, conveyed in it and dumped from it beyond the limits of area upon which said machine stands, substantially as herein described.

24. In combination, a main power-station and an outhaul-station with power mechanism, a scraper and ropes attached to the scraper of which ropes the main hauling-rope is attached by three draft-lines to connect

with a single hauling-rope, substantially as 55 and for the purpose herein described.

25. In machinery for excavating, dredging and transporting earth and other materials in combination, a main power-station and an outhaul-station with suitable power mechanism, 60 a scraper and three ropes for operating said scraper, the operation of filling the said scraper when controlled as to its angle of tilt by the backward-hauling rope restrained by a friction-brake applied to its winding-drum 65 against the forward-hauling rope drawn by its winding-drum to which power is applied while the scraper is being drawn forward by the main hauling-rope, substantially as described. 70

26. In machinery for excavating, dredging and transporting earth and other materials in combination, a main power-station and an outhaul-station with suitable power mechanism, 75 a scraper and ropes for operating said scraper, the use of a deck or decks upon which the mechanism is arranged so that an attendant may oversee the scraper throughout its course and control the scraper by means of such mechanism and ropes so that earth and 80 other materials may be filled into the scraper, transported in it and deposited from it, substantially as herein described.

27. In machinery for excavating, dredging and transporting earth and other materials 85 in combination, a main power-station, an outhaul-station, power mechanism, a scraper, operating-ropes with each rope directly attached to the scraper for operating it and brackets or lugs at the front of the scraper, as and for 90 the purpose herein described.

28. In combination for excavating, dredging and transporting earth and other materials, a scraper, ropes attached to said scraper and a machine with suitable power mechanism for operating said scraper by means of said ropes, such machine having a double cantaliver-arm bearing guide-pulleys whereby said scraper may be operated each way beyond the limits of the area upon which said 100 machine stands.

In witness whereof I have hereunto set my hand in presence of two witnesses.

GEORGE HENRY DUNLOP.
